UNITED STATES PATENT OFFICE.

GEORGE M. PAINTER, OF CHICAGO, ILLINOIS.

ELECTRIC HAMMER.

1,276,804.

Specification of Letters Patent. Patented Aug. 27, 1918.

Application filed July 20, 1917. Serial No. 181,897.

To all whom it may concern:

Be it known that I, GEORGE M. PAINTER, a citizen of the United States, and a resident of Chicago, in the county of Cook and 5 State of Illinois, have invented certain new and useful Improvements in Electric Hammers; and I do hereby declare that the following is a full, clear, and exact description thereof, reference being had to the accompanying drawings, and to the letters of reference marked thereon, which form a part of 10 this specification.

This invention relates to improvements in 15 electric hammers and consists of the matters hereinafter described and more particularly pointed out in the appended claims.

The object of the invention is to provide 20 a hammer of the kind illustrated and described in an application filed by myself on January 2, 1917, and bearing Serial Number 140,055, which will be more efficient in operation, easier to assemble and which may be manipulated so that the impact member 25 will move either slow or fast, as the occasion demands.

A further object of the invention is to so construct and arrange the parts, that the weight and length of the hammer may be reduced considerably without detracting 30 from its efficiency in operation.

These objects as well as the several advantages of my improved electric hammer will be more apparent as I proceed with my specification.

35 In the drawings:

Figure 1 illustrates a view in side elevation of my improved electric hammer.

Fig. 2 illustrates, on an enlarged scale, 40 a longitudinal, central section through the same.

Figs. 3, 4 and 5 illustrate transverse, sectional views through the hammer, the planes of the various sections being indicated respectively by the lines 3—3, 4—4 and 5—5 45 of Fig. 2.

Figs. 6, 6^a and 6^b, represent respectively, fragmentary diagrammatic views of an electric circuit which, when considered collectively, illustrate the layout of the circuit 50 connecting wires used in my improved electric hammer.

Referring now to that embodiment of my invention illustrated in the accompanying drawings:—10 indicates the body of the tool or hammer, which is in the form of an elongated tube or barrel 11. Said barrel has a

closed head 12, at one end and a tool retaining cap 13 at its other, the head and the cap being threaded upon the ends of the barrel as in the case of a pneumatic hammer. The 60 head 12 provides a handle for the tool or hammer and the cap 13 provides a bearing and support for a tool holder 14, which has a recess 15, adapted to receive the shank of an operating tool 16. Fitting snugly against the inner wall of the barrel 11 is a tube of insulating material 17 which extends the 65 full length of said barrel.

The barrel 11 is divided longitudinally 70 into two chambers, one of which is longer than the other; that is an elongated, solenoid chamber 19 at the cap end of the barrel and a shorter, commutator chamber 20 at the head end of the barrel.

21 indicates a plurality of separate solenoids which are connected in series and arranged end to end in succession in the chamber 19, with their common axes coincident with the longitudinal, central axis of the barrel 11. The solenoids are preferably in the 75 form of flat, annular coils and they are held in place as shown by oppositely facing, end plates or disks 22, 23, which are connected together by angularly spaced, longitudinally extending rods 24. Said rods engage the 80 peripheries of the solenoid coils in a manner holding them in alinement. The endmost coils 21 are insulated from the associated disks 22, 23, by means of insulating washers 22^a, 23^a. The disks 22, 23, bear 85 within the insulating sleeve 17 and have tubular flanges 22^b, 23^b, respectively. The flange 22^b of the disk 22 has a thrust bearing against the end cap 13, while the flange 23^b of the disk 23 is adapted to receive the 90 inner end of a rotative shaft 25, the purpose of which will presently appear.

26 indicates a longitudinally extending tube of insulating material which is arranged coaxially with the shell 11, within 95 the solenoids 21. This tube is supported at its ends in the disks 22, 23, and has a plurality of angularly spaced, longitudinal slots 27 (see Figs. 2 and 3) which open through the rear end of said tube. A 100 washer 28 of insulating material is provided to hold the rear end of said tube against collapse. In each of said slots 27 is provided a longitudinal bar or T-shaped rail 29, with its body flange arranged radially 105 and extending into the interior of said tube 26 and with its laterally extending head

flange arranged in the space between said tube and the solenoid coils 21. The disk 28 at the rear end of the tube 26 has a plurality of angularly spaced notches in its periphery to receive the body flanges of the bars 29.

30 indicates a core which has longitudinal sliding bearing upon the body flanges of the bars 29, within the tube 26. This core is 10 laminated longitudinally and comprises a plurality of longitudinal bars 31 held in place between end rings 32, 32. Said core has longitudinal grooves in its periphery, into which body flanges of the bars 29 extend. It is thus apparent that while said core may freely reciprocate longitudinally on the bars 29, it is held against rotative movement.

In the commutator chamber 19, near the 20 head 12, is provided a motor 35 and the armature shaft of said motor is operatively connected to the shaft 25 before mentioned. Said motor is suitably held in place by rings 36 and 37, the ring 36 which engages 25 the front end of said motor being fixed in place by screws 36^a, extending through the barrel 11 and insulating tube 17, while the ring 37 which engages the rear end of the motor has screw threaded engagement with 30 the insulating tube 17. A short sleeve 37^a of insulating material is interposed between the ring 37 and the head 12 to prevent displacement of the ring 37. As shown, the sleeve 37^a has screw threaded engagement 35 with the head end of the long sleeve 17.

Located in the chamber 19, near the disk 28 and near the motor 35 respectively, are cross connection boards 38 and 39, which consist of disks of insulating material. 40 These boards or disks are held in place against shifting and against rotative movement by screws 40 which extend through the sleeve 17 into the body of said boards or disks. The cross connection or wiring on 45 said boards or disks will be described later in connection with the other wiring forming the circuit of the tool or hammer as a whole.

Associated with said cross connection boards, are commutator disks 41, 42, respectively. Said commutators are placed adjacent the opposed faces of the associated disks 38 and 39, and are non-rotatively fixed thereto by means of sleeves 43, through which the shaft 25 extends and has rotative 55 bearing. Said commutators are of the usual construction, comprising segments which are insulated from each other. Fixed to the opposed faces of said commutators and insulated therefrom are collector rings 44, 45, in the form of metallic disks, of a diameter somewhat smaller than that of the associated commutator. The commutators 41, 42, are connected in circuit to the associated cross connection boards in a manner presently to be described.

Fixed to the shaft 25 between the collector rings 44, 45, is a disk 46 of insulating material which is and will be hereinafter referred to as a brush holding disk. Mounted on said disk approximately diametrically opposite each other and near the periphery, are carbon, distributor brushes 47, 48, which have wiping engagement with the faces of the segments of the commutators 41 and 42. Said carbon brushes are mounted in the usual manner, in tubes having springs which maintain said carbon brushes in engagement with said segments. Associated with said carbon brushes and electrically connected therewith are take-off brushes 49 and 50 respectively, which are in the form of flat leaf springs that have wiping engagement with the peripheries of said collector rings 45, 46, respectively.

Upon the inner surface of the head 12, 85 is mounted a resistance coil 51 which is connected to one brush of the motor 35. This resistance member has contacts 51^a which are adapted to be engaged by a switch lever 53 pivoted on said head in a position 90 to be conveniently manipulated by the hand of the operator.

54 indicates the positive wire of the main line circuit, which is connected to the collector ring 44 and 55 indicates the negative 95 wire of said main line circuit which is connected to the other collector ring 45. A lead wire 54^a connects the positive line wire 54 to the other brush of the motor and a lead wire 55^a connects the negative line wire 55 100 to the lever 53. It is apparent that the speed of the motor armature shaft may be readily controlled by the lever 53.

I will now describe the circuit wire connections between the solenoids 21 and the 105 cross connection boards 38, 39, and the circuit wire connections between said boards and the associated commutators 41 and 42 respectively. In Fig. 6 is illustrated diagrammatically, the several solenoid coils 21 110 which are numbered consecutively from 1 to 40 for the sake of convenience. The first thirty-one solenoid coils (numbered 1 to 31) are tapped by bridge pieces 21^x shown in Fig. 6 on the bottom side of said 115 solenoid coils. The last thirty-one solenoid coils (numbered 10 to 40) are likewise tapped by bridge pieces 21^y shown in Fig. 6 on the top side of said solenoid coils.

Each cross connection board 38, 39, has a 120 plurality of binding posts or pins, in this case sixty, which are spaced at equal, angular distances apart. For the purposes of following out the circuit, these pins in both cases are numbered (see Figs. 6^a and 6^b) on 125 the top halves of the said boards, from 1 to 31 in clockwise order, and on the bottom halves of said boards from 2 to 30 in counter-clockwise order. The pins numbered from 2-2 to 30-30 inclusive, on both 130

boards 38, 39, are connected together by cross wires 38^a, 39^a, respectively.

There are as many segments in each commutator as there are binding pins on each 5 cross connection board and the segments of each commutator are numbered consecutively in clock wise order from 1 to 60.

The segments numbered 1 to 31 of the commutator 41 are connected by associated wires 10 indicated at *a* in Fig. 6^a, to the binding pins numbered 1 to 31 on the top half of the cross connection board 38 while the segments numbered 32 to 60 inclusive, of said commutator 41 are connected by associated wires indicated at *a*¹ in said figure, to the binding pins numbered 30 back to 2 on the bottom half of said cross connection, to the tap-in bridge pieces 21^x of the solenoid coils numbered 1 to 31 inclusive, by a plurality of 15 wires indicated as a whole by *b*. (See Figs. 6 and 6^a).

Taking any segment of the commutator 41 as an example, say segment #16, and following up its wiring connection through 20 the board 38 it will be found that one of the wires *a* connects said segment with binding pin 16 on the top half of the board 38, then down through a wire 38^a to the pin 16 on the bottom half of the board 38, then 25 through the associated wire *a*¹ to the segment 46 of said commutator 41. Said segment 30 16 is connected to the bridge piece 21^x between the solenoid coils numbered 15 and 16 and the segment 46 also is connected to 35 the said bridge piece between the coils 15 and 16 by one of the wires *b* through one of the wires 38^a on the cross connection board 38.

The segments numbered 11 to 41 of the 40 commutator 42 are connected by associated wires indicated at *c* in Fig. 6^b, to the binding pins numbered 1 to 31 on the top half of the cross connection board 39, while the segments numbered 42 back to 10 on the bottom half of said commutator are connected by associated wires indicated at *c*¹ in said figure, to the binding pins numbered 30 back to 2 on the bottom half of the cross connection board 39. The wires *c* just mentioned are connected to the tap-in bridge pieces 21^y of the solenoid coils 10 to 40 inclusive, by a plurality of wires indicated at *d* in Figs. 6 and 6^b. Taking any segment in said commutator 42, say segment 26, and 45 following up its wiring connection through the board 39, it will be found that one of the wires *c* connects said segment with the binding pin 16 on the top half of the board 39, then down through the wire 39^a to the 50 pin 16 on the bottom half of the board 39, then through the associated wire *c*¹ to the segment 56 of said commutator 42. Said segment 26 is connected to the bridge piece 21^y between the solenoid coils numbered 25 55 and 26, by one of the wires *d* and the seg-

ment 56 is also connected to said bridge piece between the coils 25 and 26 by one of the wires *d* and through one of the wires 39^a on the cross connection board 39.

The commutators 41 and 42 are so arranged in the casing 10 that their associated brushes which are 180° apart on the brush disk 46, are but ten segments apart, so that when the brush 47 of the commutator 41 engages segments 2 of said commutator, brush 48 of commutator 42 engages segments 12 of said commutator. The circuit then, is through the collector ring 44 to brushes 47, 49, and segment 2, through associated wires *a* and *b* to the tap-in bridge piece 21^x between solenoids numbered 1 and 2, through the first ten solenoids (it being remembered that said coils are in series) out to the wires *d* connected to the bridge pieces 21^y between solenoids 11 and 12, through the associated 50 wires *d* and *c* back to segment 12 of commutator 42 through the brushes 48 and 50, to the collector ring 45. Thus, there are always ten solenoid coils energized to produce the magnetism to attract the plunger 31.

As the motor 35 imparts rotative movement to the shaft 25, said shaft will carry with it the brush disk 46, thus producing a wiping contact between the brushes 47 and 48 and the segments of the associated commutators. When the brush 48 is on segment #40 of the commutator 42, the brush 47 is on segment #30 of commutator 41. With the brushes in this position, it will be seen that solenoid coils #30 to #40 inclusive, will be energized, the intermediate coils having been energized and deenergized, producing a magnetic wave which travels through the coils, attracting and carrying with it the plunger 31 which is now at the limit of its inward stroke toward the head end of the hammer, as a whole. When brush 47 is on segment #31 of commutator 41, brush 48 is on segment #41 of commutator 42. The magnetic field will at this point be stopped momentarily and reversed so that it will again be in advance of the core, which will now move in the opposite direction, or toward the tool end of the hammer.

When brush 48 is on segment #42 of commutator 42, brush 47 is on segment 32 of commutator 41. The circuit is then through collector ring 45, brushes 50 and 48 to said segment #42, through the associated wire *c*¹ to binding pin #30 on the bottom half of board 39 through the associated cross connection wire 39^a to the pin 30 on the top half of the board 39 out through one of the wires *d* connected to the last mentioned pin 30, to bridge piece 21^y, tapping in between solenoid coils 39 and 40 through the next ten coils, out at bridge piece 21^x, between solenoid coils 29 and 30, down through the associated wire *b* to pin 30 on the top half of the board 38, through the cross connection 100

wire 38^a to pin 30 on the bottom half of said board, through the associated wire *c* to segment #30 of commutator 41, through brushes 47 and 49 and then to the collector

5 ring 44.

It is manifest from the foregoing description, that there is a pre-determined number of solenoids in excess of one half of the segments on a commutator, and that one half 10 of the segments of one of said commutators are connected in succession to the solenoids beginning at one end of the series and the corresponding half of the segments of the other commutator are connected in succession 15 to the other side of said solenoids, beginning at that one of the solenoids which is spaced from the same end of the series, by a number of solenoids substantially equal to the said pre-determined number, and that 20 each of the other half of the segments of the commutators are cross connected to the same solenoids successively but in a reverse direction and in opposite order, through the cross connection boards before mentioned.

25 As the magnetic wave thus produced, travels toward the front or tool end of the hammer, it will attract and move the plunger in the direction of the travel of the wave, the plunger striking the tool holder and 30 imparting the necessary impact to the tool 16.

It is apparent that the travel of the wave is shifted by a continuous moving member, so that there is no stopping or retarding of the means causing a reversal of the magnetic 35 wave. Thus arcing, with its attendant heat, is eliminated.

Suitable means are provided to prevent a formation of an air cushion at the tool end of the hammer. An opening 14^a in the tool 40 holder permits excess air to pass from in front of the hammer. Similar air escape ports are provided in the disks 28, 23, for the escape of such air when the plunger is moving toward the head end of the hammer, 45 but these ports need not be large, as it is desired to use some of this air to form a cushion to prevent the plunger from striking the disk 28 when it is moving in the direction just mentioned.

50 My improved electric hammer has many advantages. It is evenly balanced and operates efficiently, irregardless of the angle at which it is used. It is light in weight, when the weight of other hammers of the same 55 size and efficiency are considered, and the parts may be fully assembled before placing them within the casing.

The plunger may be caused to reciprocate at a speed proportionate to the speed of the 60 brush disk, thus there may be a reasonable variance in the number of strokes or impacts per minute, of the hammer as a whole.

While in describing my invention, I have referred to certain details of mechanical construction and arrangement of circuit wires,

I do not wish to be limited thereto, except as may be pointed out in the appended claims.

I claim as my invention:

1. An electro-magnetic motor comprising 70 a plurality of solenoids connected in series and arranged in longitudinal succession with a common axis, a core constituting a hammer, movable with respect to said solenoids, two commutators having a like number of segments, the number of solenoids exceeding one half of the number of segments of a commutator by a predetermined number, one half of the number of segments of one of said commutators being connected in 75 succession to the solenoids, beginning at one end of the series, and the corresponding segments of the other commutator being connected in succession to the other side of said solenoids, but beginning at that one of the solenoids which is spaced from the same end of the series by a number of solenoids substantially equal to the said predetermined number, and each of the other half 80 of the number of segments of the commutators being cross connected to the same solenoids successively, but in reverse direction and in opposite order. 85

2. An electro-magnetic motor comprising 90 a plurality of solenoids connected in series and arranged in longitudinal succession with a common axis, a core constituting a hammer, movable with respect to said solenoids, two commutators having a like number of segments, the number of solenoids exceeding one half of the number of segments of a commutator by a pre-determined number, one half of the number of segments of one of said commutators being connected in 95 succession to the solenoids, beginning at one end of the series, and the corresponding segments of the other commutator being connected in succession to the other side of said solenoids, but beginning at that one of the solenoids which is spaced from the same end 100 of the series by a number of solenoids substantially equal to the said pre-determined number, and each of the other half of the numbers of segments of the commutators being cross connected to the same solenoids 105 successively, but in reverse direction and in opposite order, a collector ring associated with each commutator and a rotative brush operatively connecting each collector ring 110 with the segments of the associated commutator.

3. An electro-magnetic motor comprising 115 a plurality of solenoids connected in series and arranged in longitudinal succession with a common axis, means providing angularly 120 spaced rails within said solenoids, a core constituting a hammer capable of reciprocating movement on said rails, two commutators having a like number of segments, the 125 number of solenoids exceeding one half 130

of the number of segments of a commutator by a pre-determined number, one half of the number of segments of one of said commutators being connected in succession to the solenoids, beginning at one end of the series, and the corresponding segments of the other commutator being connected in succession to the other side of said solenoids, but beginning at that one of the solenoids which is spaced from the same end of the series by a number of solenoids substantially equal to the said pre-determined number, and each of the other half of the numbers of segments of the commutators being cross connected to the same solenoids successively but in reverse direction and in opposite order, a collector ring associated with each commutator and a rotative brush operatively connecting each collector ring with the segments of the associated commutator.

4. An electro-magnetic motor comprising a plurality of solenoids connected in series and arranged in longitudinal succession with a common axis, means providing angularly spaced rails within said solenoids, a core constituting a hammer capable of a reciprocating movement on said rails, a rotative shaft in line with the axis of said solenoids, two commutators having a like number of segments, the number of solenoids exceeding one half of the number of segments of a commutator by a pre-determined number, one half of the number of segments of one of said commutators being connected in succession to the solenoids, beginning at one end of the series and the corresponding segments of the other commutator being connected in succession to the other side of the solenoids, but beginning at that one of the solenoids which is spaced from the same end of the series by a number of solenoids substantially equal to the said pre-determined number and each of the other half of the numbers of segments of the commutators being cross connected to the same solenoids successively but in reverse direction and in opposite order, a collector ring associated with each commutator, and a brush operatively connecting each collector ring with the segments of an associated commutator, said brushes being angularly spaced apart and rotative with said shaft.

5. An electro-magnetic motor comprising a plurality of solenoids connected in series and arranged in longitudinal succession with a common axis, means providing angularly spaced rails within said solenoids, a core constituting a hammer capable of a reciprocating movement on said rails, two commutators having a like number of segments, the number of solenoids exceeding one half of the number of segments of a commutator by a predetermined number, one half of the number of segments of one

of said commutators being connected in succession to the solenoids, beginning at one end of the series, and the corresponding segments of the other commutator being connected in succession to the other side of said solenoids, but beginning at that one of the solenoids which is spaced from the same end of the series by a number of solenoids substantially equal to the said pre-determined number, and each of the other half of the numbers of segments of the commutators being cross connected to the same solenoids successively, but in reverse direction and in opposite order, a collector ring associated with each commutator, a rotative brush operatively connecting each collector ring with the segments of the associated commutator, said brushes being angularly spaced apart, and means for rotating said brushes at different speeds.

6. An electro-magnetic motor comprising a plurality of solenoids, connected in series and arranged in longitudinal succession with a common axis, means providing angularly spaced rails within said solenoids, a core constituting a hammer capable of a reciprocating movement on said rails, a rotative shaft in line with the axis of said solenoids, two commutators having a like number of segments, the number of solenoids exceeding one half of the number of segments of a commutator by a predetermined number, one half of the number of segments of one of said commutators being connected in succession to the solenoids, beginning at one end of the series, and the corresponding segments of the other commutator being connected in succession to the other side of said solenoids, but beginning at that one of the solenoids which is spaced from the same end of the series by a number of solenoids substantially equal to the said pre-determined number, and each of the other half of the numbers of segments of the commutators being cross connected to the same solenoids successively but in reverse direction and in opposite order, a collector ring associated with each commutator, a brush disk fixed to said shaft, brushes on said brush disks operatively connecting each collector ring with the segments of the associated commutator, and means for rotating said shaft at different speeds.

7. An electro-magnetic tool comprising a tubular casing, a tool holder at one end of the casing and a handle at the other end of the casing, a plurality of solenoids connected in series and arranged in longitudinal succession with a common axis within the casing, means providing rails within said solenoids, a core constituting a hammer reciprocable on said rails, spaced commutators having a like number of segments in the handle end of said casing, the number

- of solenoids exceeding one half of the number of segments of a commutator by a predetermined number, one half of the number of segments of one of said commutators being connected in succession to the solenoids, beginning at one end of the series, and the corresponding segments of the other commutator being connected in succession to the other side of said solenoids, but beginning 5 at that one of the solenoids which is spaced from the same end of the series by a number of solenoids substantially equal to said predetermined number, cross connection boards adjacent each commutator connecting the 10 other half of the segments of the commutators to the same solenoids but in reverse direction and in opposite order, a collector

ring fixed to the inner face of and associated with each commutator, a rotative shaft arranged in line with the axis of said solenoids, a disk fixed to said shaft between said commutators, brushes carried by said disk and operatively connecting each collector ring with the segments of the associated commutator, and means in said casing 25 for rotating said shaft.

In testimony that I, claim the foregoing as my invention I affix my signature in the presence of two witnesses, this 12th day of July A. D. 1917.

GEORGE M. PAINTER.
